(57) **CLAIM**

The ornamental design for an information input device with multiple memory card reader, as shown and described.

DESCRIPTION

FIG. 1 is a top plan view of information input device with multiple memory card reader in a non-active (closed) position;

FIG. 2 is a right side plan view thereof;

FIG. 3 is a left side plan view thereof;

FIG. 4 is a front plan view thereof;

FIG. 5 is a back plan view thereof;

FIG. 6 is a bottom plan view thereof;

FIG. 7 is a top plan view of an information input device with multiple memory card reader in an active (“POP-UP”) position;

FIG. 8 is a right side plan view thereof;

FIG. 9 is a left side plan view thereof;

FIG. 10 is a front plan view thereof;

FIG. 11 is a back plan view thereof;

FIG. 12 is a bottom plan view thereof;

FIG. 13 is a top right perspective view of an information input device with multiple memory card reader in a non-active position; and,

FIG. 14 is a top right perspective view of an information input device with multiple memory card reader in an active position.
